Primary Examiner — Brett Miller
Assistant Examiner — Sara Michie Pottenger(57) **CLAIM**

The ornamental design for an intelligent recognition pet door as shown and described.

DESCRIPTION

FIG. 1 is a perspective view of a intelligent recognition pet door showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1; and, FIG. 10 is a partial enlarged view of portion 10 in FIG. 2. The broken lines depict portions of the intelligent recognition pet door and form no part of the claimed design.

The dash-dot-dash line is included for the purpose of illustrating the bounds of the enlarged view and forms no part of the claimed design.
